UNITED STATES PATENT OFFICE.

FREDRICK H. WALTER, OF FENNIMORE, WISCONSIN.

SPIKE.

1,112,871.

Specification of Letters Patent.

Patented Oct. 6, 1914.

Application filed March 21, 1914. Serial No. 826,312.

To all whom it may concern:

Be it known that I, FREDRICK H. WALTER, a citizen of the United States, residing at Fennimore, in the county of Grant and State of Wisconsin, have invented certain new and useful Improvements in Spikes, of which the following is a specification.

This invention relates to a railroad spike, and the principal object of the invention is to provide an improved means for securely locking the spike in a tie, and to provide improved means for slightly raising the spike after being driven into place thus bringing the locking pawl into action.

Another object of the invention is to provide a spike of the kind described which can be easily and cheaply manufactured and which is so constructed that the spike will not be weakened.

Another object of the invention is to so mount the locking pawl that the spike may be easily driven into the tie but will be prevented from working out of the tie after it has been locked in the tie.

This invention is illustrated in the accompanying drawings wherein—

Figure 1 is a view showing the spike in place before it has been locked; Fig. 2 is a view similar to Fig. 1 showing the spike locked; Fig. 3 is a fragmentary view in elevation of the lower end portion of the spike; Fig. 4 is a perspective view of the plate which raises the spike and moves the locking pawl into an operative position.

The spike 10 is provided with a rail-engaging head 11 which head has its lip provided with notches 12 so that the arms 13 extending from the plate 14 may be bent into the notches and prevent the plate from working from beneath the lip. In order to lock the spike, there is provided a pawl 15 which is pivotally mounted within the slot 16 upon the pin 17. The slot 16 is wider at its mouth than at its inner end so that the pawl may freely move vertically in the opening and thus move to an operative position. It should also be noted that the pawl has its outer end cut at an incline to form a cam edge which will hold the pawl in the position shown in Fig. 1 when driving the spike into the tie. It should also be noted that the upper edge of the pawl has its outer end portion curved inwardly as shown at 18 thus forming a sharp penetrating point at the end of the pawl.

When in use, the spike is driven into the

tie as shown in Fig. 1 with the head engaging the base of the rail 19. After the spike has been driven into the tie to the position shown in Fig. 1, the plate 14 will be driven beneath the lip of the head 11 and will raise the spike a short distance so that the spike will be moved to the position shown in Fig. 2, and the pawl swung to the position shown in this figure. The arms 13 will then be raised and moved into the notches or groove 12 thus preventing the plate from slipping out of place or worked from beneath the lip of the head 11. As the spike is driven into the tie, the pawl will be swung outwardly and therefore the spike can move into the tie without the pawl interfering with the spike being driven into place. The sharp end of the pawl which extends out of the slot or opening 16 will dig into the tie when the spike is raised thus causing the pawl to be swung downwardly to the locked position. The wood of the tie will then fill in around the spike thus leaving the spike fitting tightly in the tie and securely held in place by the locking pawl. The spike will thus be securely held in the tie and will be prevented from being worked out of the tie by the pounding or jarring of a train passing over the rails. An inspection of the drawings will readily show that the spike will not be weakened to a material extent since the opening or slot 16 is comparatively small and therefore will not cause the spike to easily break.

What is claimed is:

1. A spike provided with a transversely extending opening adjacent its penetrating end, the slot increasing in size toward its outer end, a locking pawl pivotally mounted in said slot and having its free end extending beyond the outer end of the slot with its free end cut at an incline to form a cam edge and having the outer end of its upper edge curved inwardly to form a penetrating point, a head at the upper end of said spike provided with rail-engaging lip having a seat formed therein, and a plate fitting beneath said lip and provided with arms fitting into said seat to secure said plate beneath said lip.

2. A spike provided with an opening adjacent its penetrating end, a locking pawl pivotally mounted in said opening with its free end extending beyond said spike and sharpened to form a penetrating point, a

head for said spike provided with a rail-engaging lip, a plate fitting beneath said lip, and means releasably connecting said plate with said lip.

- 5 3. A spike, a locking pawl pivotally connected with said spike with its free end extending beyond the side of the spike and cut at an incline to form a cam and terminating in a penetrating point, and means releasably connected with the head of said spike for moving said spike to a position to swing said pawl to a locked position.
- 10 4. A spike, a locking pawl carried by said spike, and means connected with the head of said spike for moving said spike to a position to move said locking pawl to a locked position.
- 15 5. A spike, a head for said spike provided with rail-engaging lip, locking means carried by said spike, and means carried by the lip of the head of said spike for moving said spike to a position to move said locking means to a locked position.
- 20 6. A spike, a head for said spike, locking means carried by said spike, means for ex-

tending beneath the head of said spike to raise said spike and move said locking means to an operative position, and means for releasably holding said last mentioned means in place beneath the head of the spike.

7. A spike provided with a head having a lip, locking means carried by said spike, and means connected with the lip of the head of said spike for raising said spike to move said locking means to a locked position.

8. A spike, a head for said spike provided with a rail-engaging lip, locking means carried by said spike, and means carried by the lip of the head of said spike for raising said spike to move said locking means to a locking position.

In testimony whereof I affix my signature in presence of two witnesses.

FREDRICK H. WALTER.
